UNITED STATES PATENT OFFICE.

WILLIAM P. WHITLEY, OF ST. LOUIS, MISSOURI, ASSIGNOR TO RAWLINGS MANUFACTURING COMPANY, OF ST. LOUIS, MISSOURI, A CORPORATION OF MISSOURI.

ABDOMINAL PROTECTING DEVICE.

Application filed December 21, 1922. Serial No. 608,244.

This invention relates to abdominal protecting devices of the kind that comprise a rigid, cup-shaped member which is adapted to be positioned over the parts of the wearer's body to be protected. As there is a natural tendency for a rigid protecting member of the kind mentioned to "work up" or move out of operative relationship with the parts to be protected, it has heretofore been the usual practice among manufacturers of athletic equipment either to equip such a protecting member with a belt and leg straps so as to enable it to be strapped in operative position, or sell the rigid protecting member in conjunction with a special form of supporter provided with a pocket in which the rigid member can be arranged and retained in the pocket by a flap on the pocket or a draw-string arranged at the upper portion of the pocket. Many athletes object to wearing a rigid protecting member equipped with leg straps and many athletes object to wearing a supporter provided with a pocket for receiving a rigid protecting member, on account of the fact that such a supporter is cumbersome and is of such design that the rigid protecting member cannot be arranged in such a position that it will be comfortable for the wearer.

Accordingly, it is the custom of many athletes to use a conventional supporter formed of elastic material and arrange a rigid protecting member inside of the supporter over the parts to be protected. This is not entirely satisfactory on account of the tendency of the rigid protecting member to "work up" or shift out of operative relationship with the parts to be protected, and therefore, I have devised a rigid protecting member for abdominal protecting devices that is capable of use with any type or style of supporter and which is equipped with means for enabling it to be detachably connected to the supporter in such a way that it will be comfortable for the user and will be held securely in operative position even when the wearer is engaged in violent exercise.

Figure 1 of the drawings is a front elevational view of a conventional elastic supporter used in conjunction with a rigid protecting member constructed in accordance with my invention.

Figure 2 is a front elevational view of said protecting member; and

Figure 3 is a front elevational view, illustrating another form of my invention.

In the drawings A designates a supporter which may be of any preferred type or kind, such, for example, as a conventional elastic supporter that is adapted to be drawn over the legs of the wearer and which is provided with a belt portion 1 and an abdominal portion 2 that extends downwardly over the abdomen of the wearer, and B designates a rigid, cup-shaped member that is adapted to be arranged inside of the supporter behind the abdominal portion 2 of same, as shown in dotted lines in Figure 1. The member B may be of any preferred style or type, such as a conventional aluminum protecting device provided at its marginal edge with a pad 3, and it is provided with a means for enabling it to be detachably connected to the abdominal portion 2 of the supporter in such a way that it cannot shift out of operative relationship with the parts of the wearer's body to be protected.

It is immaterial, so far as my invention is concerned, what type or kind of means the member B is provided with for detachably connecting it to the supporter, but I prefer to equip the member A with a safety pin C arranged on the front side of same adjacent the upper end of said member, as shown in Figure 2. Said safety pin can either be secured to the member B by a strip of tape 4 attached at its opposite ends to the member B and arranged vertically on the front side of said member, or, it can be secured to the member B by a metallic device 5 that embraces a portion of the safety pin C, as shown in Figure 3, said safety pin being arranged in such a way that it extends transversely of the protecting member B. In practice I prefer to use a piece of tape 4 for securing the safety pin to the protecting member B, on account of the fact that a piece of tape permits of a slight lateral movement of the rigid member B relatively to the abdominal portion 2 of the supporter, thereby reducing the tendency of the abdominal portion of the supporter to exert a pull on the member B in a direction tending to displace said member every time the abdominal portion of the protector shifts in conforming to the movements of the wearer's body.

From the foregoing it will be seen that my invention makes it possible for an athlete

to wear a conventional elastic supporter in conjunction with a rigid, cup-shaped protecting member without the necessity of continually moving the protecting member back 5 into operative position, as is necessary when the ordinary rigid, cup-shaped protecting member is used in conjunction with a conventional elastic supporter; it insures a greater degree of comfort to the wearer than 10 can be secured with an elastic supporter equipped with a cumbersome pocket for receiving a rigid, cup-shaped protecting member and it overcomes the necessity of using leg straps to retain a protecting member of 15 the kind referred to in operative relationship with the parts to be protected.

Having thus described my invention, what I claim as new and desire to secure by Letters Patent, is:

20 1. An abdominal protecting device of the character referred to consisting of a sub-

stantially cup-shaped, rigid member adapted to be arranged inside of a supporter and set in a position where it is comfortable to the wearer, a strip of fabric stretched across the front side of said member and having its end portions attached to said member and its intermediate portion unattached to said member, and a fastening device for detachably connecting said tape to the supporter.

2. An abdominal protecting device of the character referred to consisting of a substantially cup-shaped metallic member provided at its marginal edge with a pad, a piece of tape arranged vertically on the front side of said member and secured to the upper and lower ends of said member, and a transversely-disposed safety pin connected to said tape for enabling said member to be secured to a supporter.

WILLIAM P. WHITLEY.
